COMBINATION LAMP BASE AND CABINET

John H. Miller, Kingsville, Md.

Application July 22, 1955, Serial No. 37,097

Term of patent 14 years

(Cl. D48—20)

Fig. 1.

Fig. 3.

Fig. 2.

The dotted lines shown in the drawings are for illustrative purposes only.

I claim:

The ornamental design for a combination lamp base and cabinet, as shown and described.
